UNITED STATES PATENT OFFICE.

JAMES R. RANGE, OF RAPID CITY, SOUTH DAKOTA.

CLAMP FOR HOLDING NIPPLES UPON NURSING BOTTLES.

Application filed January 29, 1924. Serial No. 639,345.

To all whom it may concern:

Be it known that I, JAMES R. RANGE, a citizen of the United States, residing at Rapid City, in the county of Pennington 5 and State of South Dakota, have invented certain new and useful Improvements in Clamps for Holding Nipples upon Nursing Bottles, of which the following is a specification, reference being had to the accompanying drawings.

This invention relates to an improved clamp for use in holding a nipple upon a bottle, and one object of the invention is to provide a clamp which is so constructed that 15 the nipple may be very firmly held in engagement with the bottle. It very often happens that after the nipple has been put in place upon a bottle, the baby or small child will pull the nipple off, thus allowing 20 the milk to escape. This not only causes a waste of milk but also causes the milk to flow over the nightgown the child is wearing and cause the nightgown and also the blankets and sheets on the crib to be soaked 25 with the milk. The improved clamp has, therefore, been devised not only so that it can securely clamp the nipple to the bottle, but also so that the small child cannot readily grasp the latch and move the latch 30 to a releasing position.

Another object of the invention is to so construct this clasp and so connect it with the strip forming the body of the clamp that when in the closed position it may fit 35 very close to the nipple with its outer face projecting only a very short distance from the outer face of the strip forming the body of the clamp.

Another object of the invention is to so 40 construct this clamp that the body portion and the clasp may be formed of sheet metal and connected by wire links, thus permitting the clamp to be cheaply produced and sold at a small cost.

45 This invention is illustrated in the accompanying drawings wherein:

Figure 1 is a view in side elevation showing a nipple secured upon a bottle by means of the improved clasp;

50 Figure 2 is a transverse sectional view taken along the line 2-2 of Figure 1 and showing the clasp in top plan;

55 Figure 3 is a transverse sectional view taken along the line 3-3 of Figure 1 and showing the clasp in section; and

Figure 4 is a perspective view of the clasp.

This improved clamp is for use in connection with bottles to retain the nipple thereon and while it has been shown used in connection with a bottle B of the large neck type carrying a nipple N for fitting upon the open end of this bottle, it will be understood that by making the clamp of the proper size it could also be used in connection with bottles of the small neck type. 60 It will, therefore, be seen that the clamp can be used in connection with bottles and nipples of any conventional construction in which the nipple fits over the open end of the bottle. 65

This improved clamp is provided with a body portion 1 formed of a strip of sheet metal which may be of resilient material if so desired but does not need to be resilient. The strip will be formed the desired length 70 according to the type of bottle with which the clamp is to be used and has its end portions formed into sleeves 2 and 3 in which are loosely mounted the links 4 and 5. These links 4 and 5 are formed of wire and 75 are rectangular in shape. When the clamp is in a releasing or inoperative position the links are in spaced relation to each other but when the clamp is in a tightened position about the nipple, the links will be 80 moved into overlapping relation to each other, thereby causing the end portions of the sheet metal strip 1 to be drawn towards each other and this strip held tightly about 85 the nipple. 90

In order to draw the links and the end portions of the strip towards each other and retain them in this clamping position, there has been provided a latch which is indicated in general by the numeral 6 and intermediate its length is loosely connected with the link 4. One end portion is loosely connected with the link 5 and the other end portion is provided with a bill for locking engagement with the sleeve 3. It will be 95 readily understood that when the latch is moved to swing the bill portion thereof into engagement with the sleeve 3, the other end portion will be swung to draw the link 5 beneath the link 4 and thereby reduce the 100 diameter of the space enclosed by the strip 1. This latch 6 is preferably formed from a strip of sheet metal doubled intermediate its length to provide a body portion 7 which has one end portion doubled and folded 105 110

downwardly and inwardly to provide a bill 8, the free end portion of which is curved as shown at 9. This bill is of sufficient length to permit its free end portion to engage the sleeve 3 and snap beneath the sleeve when the lever is moved to swing the free end portion of the lever downwardly towards the sleeve 3. The upper or outer leaf of the strip forming the latch extends 10 beyond the end of the lower leaf and this extended end portion is rolled to provide a bearing sleeve 10 in which is positioned one end portion of the link 5. The shorter inner leaf of the latch forming strip is also 15 rolled to provide a sleeve 11 positioned intermediate the sleeve 10 and free end of the bill 8. The latch lever extends through the link 4 and the sleeve 11 receives the end bar of the link 4. It should be further noted 20 that the links 4 and 5 are of such length and the sleeves 10 and 11 spaced apart to such an extent that when the latch lever is swung to the locking position, the sleeve 10 will be positioned in the link 4 between the sleeves 25 2 and 11 and the sleeve 11 will be positioned in the link 5 between the sleeves 10 and 3. It will be therefore noted that the sleeves will be all located in substantially the same plane and will fit in close engagement with 30 the portion of the nipple positioned about the open end of the bottle.

When this device is in use the nipple is placed upon the bottle in the usual manner and the clamp will then be placed about 35 the portion of the nipple fitting upon the bottle. After the clamp has been put in place about the nipple, the latch lever will be forced towards the locking position and this action will cause the link 4 to be drawn 40 into overlapping relation to the link 5. This will cause the band or strip 1 to be drawn tightly about the nipple and firmly bind the nipple upon the bottle. When the curved free end portion of the bill 8 of this latch 45 lever engages the sleeve 3 additional pressure will be applied and the bill will snap into place beneath the rounded side portion of the sleeve where it will be held by the frictional binding between the sleeve and the 50 resilient bill portion of the latch. When in this position the nipple will be firmly held in place and cannot be pulled from the bottle until the latch has been forced outwardly to a releasing position. In view of the 55 fact that the free end portion of this latch fits very close to the nipple it cannot be readily grasped and swung outwardly to a releasing position by the small child and therefore there is no danger of the nipple 60 being pulled off of the bottle and permit the milk to pass out of the bottle. While the lever has been described as being formed of sheet metal, it will be understood that this 65 latch lever could be formed in other ways, it being essential, however, that it be curved

longitudinally to conform to the shape of the bottle and have the inturned bill at one end, its sleeve at the other end and the second sleeve intermediate the first sleeve and the free end of the bill.

What is claimed is:—

1. A nipple securing clamp comprising a substantially circular body portion formed of a strip of material and having sleeves at its ends, open links loosely mounted in said sleeves and extending towards each other and adapted to be moved into overlapping relation, and a latch lever having a longitudinally curved body portion extending through one of said links and having a bearing sleeve extending transversely across its under face and intermediate its length and loosely fitting upon the last mentioned link, the inner end of said latch lever being provided with a bearing sleeve extending across its inner face and loosely receiving the outer end portion of the other link, the outer end portion of said latch lever being provided with a bill extending beneath the under face of the lever and adapted to have frictional engagement with a sleeve of the body forming strip to secure the latch when the latch is swung to the locking position.

2. A nipple securing clamp comprising a body portion formed of a strip having its end portions provided with bearing sleeves, a link loosely mounted in the bearing sleeve at one end of said strip and a second link loosely mounted in the bearing sleeve at the other end of said strip, said links being adapted to be moved into overlapping relation to draw the ends of the strip towards each other, said bearing sleeves being positioned outwardly from the outer face of said strip, and a latch including a longitudinally curved body portion having one end portion extending through the first link and provided intermediate its length with a bearing sleeve extending across its under face and loosely mounted upon the outer end portion of the first link, the end portion of said lever being provided with a bearing sleeve extending across its under face and loosely receiving the outer end portion of the second link and adapted to fit into the first link when the lever is swung to a locking position with the sleeve intermediate the length of the latch positioned within the second link and the links in overlapping relation to each other and a bill extending beneath the free end portion of said lever for frictionally engaging with the sleeve carrying the second link to releaseably hold the latch lever in a locking position.

3. A clamp for securing a nipple about a bottle, said clamp comprising a strip having its end portions rolled outwardly to provide bearing sleeves, links loosely fitting in said sleeves, and a latch lever for draw-

- ing said links into overlapping relation and tightening said strip about the nipple, said latch lever being formed from a strip of material doubled intermediate its length to 5 provide a body portion, the doubled strip being further bent to provide an inwardly extending bill having its free end portion curved to snap beneath the sleeve at one end of the strip when the latch is in a locking position, the inner leaf of said folded strip being rolled to provide a depending 10 sleeve loosely receiving the outer end portion of one of said links and the outer leaf of the folded strip being projected beyond the last mentioned sleeve and through the last mentioned link and rolled inwardly to provide a sleeve loosely receiving the outer end portion of the other link.

In testimony whereof I hereunto affix my signature.

JAMES R. RANGE.
